UNITED STATES PATENT OFFICE.

JAMES A. MCCOLLUM, OF PAWNEE, OKLAHOMA.

RADIATOR ATTACHMENT.

1,262,074.

Specification of Letters Patent. Patented Apr. 9, 1918.

Application filed February 8, 1918. Serial No. 216,044.

To all whom it may concern:

Be it known that I, JAMES A. MCCOLLUM, a citizen of the United States, residing at Pawnee, in the county of Pawnee and State 5 of Oklahoma, have invented a new and useful Radiator Attachment, of which the following is a specification.

The device forming the subject matter of this application is adapted to be attached to 10 the cap of the radiator of an automobile, to serve as an ornament.

One object of the invention is to provide a structure of the kind mentioned, which may be fashioned at trifling expense out of sheet 15 metal or some similar substance.

Another object of the invention is to provide novel means for mounting the attachment for movement with respect to the radiator cap.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

In the accompanying drawings:

Figure 1 shows in side elevation, a device 35 constructed in accordance with the invention;

Fig. 2 is a section on the line 2—2 of Fig. 1, a part of the upper plane remaining in 40 elevation;

Fig. 3 is a section on the line 3—3 of Fig. 2;

Fig. 4 is a section on the line 4—4 of Fig. 2, different parts being omitted; and

Fig. 5 is an elevation showing a slight 45 modification, parts being broken away.

The structure forming the subject matter of this application preferably is made of metal throughout and includes an upper 50 plane 1 provided on its front and rear edges and near its central portion with underlying flanges 2. The numeral 3 marks a lower plane, provided with overhanging flanges 4 aligned vertically with the flanges 2 on the 55 plane 1. Disposed between the planes 1 and 2 at the corners thereof are struts 5 having

lateral fingers 6 which engage the inner surfaces of the planes 1 and 2, the struts having fingers 7 which pass through the planes 1 and 2 and engage the outer surfaces thereof, the construction being such that the planes 1 and 2 are held together against separation and against moving toward each other.

The invention comprises a body 8 located 60 between the planes 1 and 2, the body comprising a bottom 9 resting on the lower plane 3 and engaged at its front and rear edges by the flanges 4 of the plane 3, the bottom 9 being provided along one edge with an upward flange 10. A side 11 upstands from the opposite edge of the bottom 9 and is connected with a top 12 bearing against the under surface of the upper plane 1 engaged at its end by the flanges 2 of the upper plane. 70 A side 14 extends downwardly from the top 12 and bears against the outer surface of the flange 10, the flange 10 having a tongue 15 extended through the side 14 and clenched down thereon, the construction being such 75 that the bottom 9, the side 11, the top 12 and the side 14 will be held in box-like form. The rear ends 16 of the sides 11 and 14 extend backwardly beyond the bottom 9 and the top 12 and converge, the rear extremities 80 of the parts 16 being in contact as shown at 17, and being supplied with outwardly projecting wings 18. One of the contacting portions 17 of the body is provided with a bendable tongue 19 extended through the 85 other contacting portion and clenched down thereon to hold the parts 17 together. The forward extremity of the side 11 merges into a transverse end wall 20, extended as shown at 21, so as to overlap the outer side of the 90 member 14, the extension 21 having a tongue 22 prolonged through the side 14 and clenched down thereon. The side 14 merges into a transverse end wall 23 disposed to the rear of the end wall 20 and terminating 100 in a tongue 24 extended through the forward extremity of the side 11 and clenched thereon.

A shaft 25 is mounted in the end walls 23 and 20 and is butt ended as shown at 26, to 105 engage the end wall 23. A dummy propeller 27 is journaled on the shaft 25 in front of the end wall 20. A boss 28 is struck up from the upper plane 1 between the sides 11 and 14 of the body and receives rotatably, a head 110 29 on one part 30 of a standard 31, the part 30 of the standard passing vertically down-

ward through a top 12 of the body 8, the top of the body having a complementary boss 40 wherein the head 29 is received. The construction, obviously, is such that the aeroplane above described is journaled to rotate on the part 30 of the standard 31. The standard 31 includes a lower part 32 spaced laterally from the part 30 of the standard and united therewith by a horizontal connection 33. The numeral 34 marks a radiator cap having a stem 35 fashioned into a helix 36. The lower part 32 of the standard 31 is journaled for rotation in the helix 36, the connection 33 resting on top of the helix, to support the standard 31, and consequently to support the aeroplane.

If desired, the stem may be straight, as shown at 38, the numeral 37 marking the cap wherewith the stem is assembled, the head of the stem, corresponding to the part 29, being indicated at 39. Aside from the changes made in the standard, this form of the invention is constructed like the form above described.

25 The aeroplane can rotate on the upper part 30 of the standard 31, and the lower part 32 of the standard can rotate in the helix 36. Consequently, the aeroplane is mounted for rotation about an axis, and to travel in an orbit.

It is to be observed that the body 8 is fashioned from a single piece of metal, the cost of the device being kept down accordingly, and the number of joints being reduced to a minimum.

Having thus described the invention, what is claimed is:

1. In a device of the class described, a standard comprising horizontally offset upper and lower parts and a connection therebetween; a miniature aeroplane journaled for rotation on the upper part; and a support wherein the lower part is journaled.

2. In a device of the class described, a miniature aeroplane embodying upper and lower planes and a box-like body between the planes, the planes having flanges engaging the top and the bottom of the body.

3. In a device of the class described, a miniature aeroplane comprising an upper plane; a lower plane; a box-like body between the planes, the body including sides extended rearwardly beyond the planes, the sides being extended forwardly beyond the planes, the forwardly extended portions of the sides having end walls; a shaft carried by the end walls; and a dummy propeller mounted on the shaft.

4. A miniature aeroplane comprising a body including a bottom having an upstanding flange, a side upstanding from the bottom, a top projecting from the side, and a second side extending downwardly from the top and overlapped on the flange, the sides having rear extensions which converge into contact, the sides having forward extensions provided with transverse end walls located one behind the other; a shaft carried by the end walls; a dummy propeller on the shaft; an upper plane mounted on the top; and a lower plane mounted on the bottom.

5. In a device of the class described, upper and lower planes; a box-like body between the planes and including a top; and a standard comprising an enlarged head journaled for rotation between the top and the upper plane, the standard passing downwardly through the body and through the lower plane.

In testimony that I claim the foregoing as my own, I have hereto affixed my signature in the presence of two witnesses.

JAMES A. MCCOLLUM.
